UNITED STATES PATENT OFFICE.

JAMES H. FOOTE, OF CINCINNATI, OHIO.

SHEAVE HOUSING.

Application filed September 21, 1922. Serial No. 539,638.

My invention relates to that class of housings intended for mounting in a mounting frame and to serve as a journal support for a sheave, and more particularly, to the form and manner of arrangement of the parts for releasably locking the housing to the mounting frame; the object of the present improvement being to provide a cheaply constructed housing that may be easily and expeditiously positioned and releasably locked in the aperture formed for it to seat in the mounting frame through changes in relative position of the parts that may be brought about by simple manipulation, thus effecting an economy by avoiding the use of screws or similar securing devices and obviating necessity for use of a tool; another object being to provide a face plate embodying means to take the end thrust of the casing without transmitting strain to the face plate itself, thus permitting the use of exceedingly thin metal for the face plate and doing away with the necessity and corresponding expense, of countersinking around the aperture formed in the mounting frame for the reception of the housing, to accommodate the face plate.

These and other objects I attain by mechanism such as shown in the accompanying drawing, in which:—

Figure 1 is a view in front elevation of a sheave housing embodying my invention, the position a sheave would occupy being indicated by dotted lines; Fig. 2 is a view in rear elevation of the face plate shown in Figure 1, with the casing removed; Fig. 3 is a view in front elevation of the casing with the face plate removed; Fig. 4 is a sectional view taken on the line *b*—*b* of Fig. 3, looking toward the upper end of the casing; Fig. 5 is a view similar to Fig. 4, but looking toward the lower end of the casing and in which the position the lower tongue of the face plate would normally occupy, is indicated in dotted lines; Fig. 6 is a view similar to Fig. 5, but showing the side walls at the lower end of the casing sprung apart somewhat by the forwardly movement of the lower tongue of the face plate, substantially the position this tongue would assume upon upwardly movement of the face plate, being indicated by dotted lines; Fig. 7 is a view in vertical section taken on the line *a*—*a* of Fig. 1, showing the housing positioned in a

fragmentary vertical section of a mounting frame with the face plate in engagement with the face of the casing in normal closed and locked position, the position the sheave would occupy being shown in dotted lines; Fig. 8 is a view in side elevation of a completed housing embodying the invention with a sheave mounted in it, showing the face plate with its upper end moved outwardly from the casing into open position and the housing positioned for entering the aperture in a mounting frame, which latter is shown in fragmentary vertical section, and having a portion of the side wall at the upper and lower front end of the casing broken out to more clearly show the then relative position of the cooperating parts of casing and face plate.

Similar numerals refer to similar parts throughout the several views.

While I have preferably shown the casing and face plate of my improved sheave housing each as formed from a single piece of sheet metal, it will be understood, that these parts or either of them, may be formed in other ways and by other means than a single piece of sheet metal by well known processes now in common use, and that the particular manner of supporting the sheave therein is not material in so far as the present invention is concerned.

My improved sheave housing consists, substantially, of a casing 1 preferably formed of sheet metal, bent to form an upper cross wall 2, by which are spaced a pair of side walls 3, 4, in each of which a centrally disposed opening 5 is formed to provide an end support for a sheave journal 6.

Side walls 3, 4, are spaced apart at their lower ends by bending inwardly a forwardly disposed end portion of each to meet on a median line and form a cross wall 7, which also may serve to take the thrust of casing 1 against the end of an aperture 8, formed in a mounting frame 9, for casing 1 to fit into.

Casing 1 is provided with an upper extension 10, which may be formed by cutting loose and bending outwardly and backwardly a tongue of the metal from cross wall 2, to pull back casing 1 at its upper end into aperture 8, of mounting frame 9.

Extension 10 is preferably curved backwardly at its upper end to provide against catching upon the upper rear edge of aper-

ture 8 in case an abnormally thick mounting frame is engaged, and in which event extension 10 may be forced to yield and become permanently bent somewhat further 5 backwardly as the housing is moved to seated position in aperture 8, or, if preferred, extension 10 may be provided with forwardly facing edges at its upper end, adapted to dig, with a backwardly forcing 10 tendency, more or less deeply into a rear face of mounting frame 9, to pull back casing 1 at its upper end into aperture 8, irrespective of a considerable range in thickness of the mounting frame engaged.

15 Casing 1 is also provided with a lower extension 11, which may be formed from a rearwardly disposed lower end portion of each of side walls 3, 4, and may have forwardly facing rearwardly beveled front edges 12, 13, thus forming an extension adapted to embed more or less deeply in the rear face of mounting frame 9, as casing 1 is seated in aperture 8, irrespective of a considerable range in thickness of the particular mounting frame engaged.

20 Casing 1 is further provided at the front with means which may take the form of flanges 14, 15, at its front edges, adapted to engage a front face of mounting frame 9 and arrest the passage of casing 1 in one direction into aperture 8, and clamp mounting frame 9 between the rear faces of flanges 14, 15, and the forwardly facing faces of extensions 10 and 11.

25 And a face plate 16, also preferably formed of sheet metal, having a centrally disposed aperture 17 at the upper end of which a tongue 18 of the metal displaced to form aperture 17, is turned inwardly and 30 provided with an upwardly turned extension 19 to occupy a space between the outer face of cross wall 2 of casing 1 and the upper end of aperture 8 and prevent upward movement of the housing when positioned 35 in aperture 8.

30 Extension 19 is provided with a reduced portion 20 adapted for inwardly and outwardly passage through a runway 21 extending backwardly from the front edge of upper cross wall 2 of casing 1, upon the side edges of which reduced portion 20, offsets 22, 23, are formed to fit into passages 24, 25, extending laterally from the side edges of runway 21 at its inner end, lock face plate 16 against outwardly movement at the upper end, and also to engage flanges 26, 27, which are turned upwardly at front edges of cross wall 2, upon opposite sides of runway 21, to provide detents and limit the outwardly movement of the upper end 55 of face plate 16.

60 Extension 19 is also provided with downwardly facing bearing faces 28, 29, adapted to engage the outer face of cross wall 2, of casing 1 upon opposite sides of runway 21,

and limit the bodily downward movement of face plate 16, and is further provided with an upper bearing edge 30 for engagement with the upper end of aperture 8, thus adapting extension 19 to serve as means in 70 cooperation with the end of aperture 8 to take the end thrust of casing 1 without transmitting strain to face plate 16 itself.

75 Tongue 18, moreover, is provided with upwardly facing faces 31, 32, to engage the under inner face of cross wall 2, of casing 1 and limit the bodily upward movement of face plate 16.

80 Formed from a part of the metal displaced to form face plate aperture 17 and bent inwardly at the lower end of said aperture, is a tongue 33, terminating in a laterally extended enlargement 34, the side extensions 35, 36, of which are each provided with a forwardly facing, backwardly beveled edge 37—38 adapted to engage a rearwardly facing edge of each of side walls 3, 4, to provide which a pair of slots 39, 40, are preferably formed one in each side wall 3, 4, of casing 1 and into which the side extensions 35, 36, of enlargement 34, may be adapted to fit, or this engagement may be directly upon the rearwardly facing edges of side walls 3, 4, and slots 39, 40, eliminated.

90 The arrangement is such that forward movement of tongue 33, will result in a wedging apart slightly of side walls 3, 4, at their lower ends by reason of the action of the forwardly facing beveled edges 95 37—38 of side extensions 35, 36, in sliding engagement with the front edges of slots 39, 40.

95 At the lower end of the front face of casing 1 side flanges 41, 42, may be bent inwardly to form an engagement for the under side of face plate tongue 33, thus providing additional means for limiting the bodily downward movement of face plate 16, and if desired, slight depressions 43, 44, 100 may be provided at the base of upturned flanges 26, 27, upon the upper face of cross wall 2, of casing 1, for offsets 22, 23, of face plate extension 19 to fit into to better maintain face plate 16 in open position to facilitate entering the housing into frame aperture 8.

105 To assemble for use, a sheave is first mounted on a journal for which a shoulder rivet may be used, between side walls 3, 4, 110 by passing the ends 6 of the rivet, through openings 5 in walls 3, 4, provided to receive them and support the journal, a face plate 16 is then positioned as shown in Fig. 7 and the outwardly extending rivet ends 6 115 headed up upon the outer faces of side walls 3, 4, of casing 1.

120 For use face plate 16 is first pushed upwardly in sliding engagement with the front face of casing 1 and the movement contin-

ued until offsets 22, 23, of face plate extension 19, have passed upwardly out of passages 24, 25, in cross wall 2 of casing 1.

Face plate 16 is then pulled forwardly at its upper end with the downwardly facing faces of offsets 22, 23, of face plate extension 19, substantially in sliding engagement with the outer face of cross wall 2 of casing 1, and this forwardly movement continued until arrested by engagement of the forwardly facing faces of offsets 22, 23, with the rearwardly facing faces of flanges 26, 27, of cross wall 2 of casing 1, when face plate 16 will have assumed, substantially, the position relative to casing 1, shown in Fig. 8.

As face plate 16 moves upwardly in sliding engagement with the face of casing 1, lower tongue 33 is carried upwardly at its point of juncture with the face plate and forwardly at its rear end, moving forwardly the forwardly facing backwardly and outwardly beveled edges 37-38 of side extensions 35, 36, in sliding engagement with the rearwardly facing front edges of slots 39, 40, and wedging apart slightly side walls 3, 4, of casing 1 at the lower end.

The tendency of walls 3, 4, to spring together again, develops a force tending to pull tongue 33 backwardly and face plate 16 backwardly and downwardly into normal closed and locked position and adapts face plate 16 for reciprocal movement.

As the upper end of face plate 16 moves outwardly from casing 1 the pressure of the downwardly facing faces of offsets 22, 23, of extension 19 upon the outer side of cross wall 2 of casing 1, increases and will ordinarily be found sufficient when offsets 22, 23, have come into engagement with flanges 26, 27, of cross wall 2, to frictionally maintain the upper end of face plate 16 in open position substantially as shown in Fig. 8, or if preferred, depressions 43, 44, may be provided for retaining engagement with offsets 22, 23, to more positively maintain face plate 16 in open position at its upper end.

With the parts in this position the housing is entered, upper end first, into the frame aperture, the lower end pushed back and the housing then seated by a bodily downwardly movement with the lower cross wall 7 of casing 1 in engagement with the lower end of the frame aperture and the upper end of extension 19 of the face plate, substantially in line with the upper end of the frame aperture.

A mere touch will then suffice to release the face plate from open position at its upper end, allowing it to move into closed position, with the upper portion of extension 19 of upper tongue 18 interposed between the top of casing 1 and the end of the frame aperture, and to move downwardly into locked position, with offsets 22, 23, fitted

into passages 24, 25, and lower tongue 33, drawn backwardly into normal position in slots 39, 40, by the springing together again of walls 3, 4, of the casing.

To remove the housing from the mounting frame it is only necessary to move the face plate upwardly and at its upper end outwardly, into position described for entering the frame aperture, raise the housing bodily upward until the extension at lower end of casing 1 clears the inner lower edge of the frame aperture, draw the housing forwardly, lower end first, and remove it from the aperture.

The face plate as shown in the drawing, is provided with a centrally disposed slightly embossed portion to overlie flanges 14, 15, at front of casing 1, as well as to stiffen the plate to avoid buckling when pulled out into open position at its upper end, and a surrounding flat edge portion, to overlie the front face of the mounting frame around the frame aperture in closely fitting engagement, to avoid the necessity of countersinking around this aperture to accommodate flanges 14, 15, and face plate 16, and effect an economy in making the frame.

Thus I have shown and described a sheave housing adapted through the form and manner of arrangement of its parts, for locking engagement with a mounting frame irrespective of considerable range in relative thickness of the particular frame engaged, and provided with a non-resilient face plate entirely devoid of undue strain and embodying features characteristic of a resilient plate.

A housing, moreover, that may be installed in a mounting frame with extreme ease and rapidity.

Advantageous features opening for the device a wide field of utility that otherwise would remain closed.

Of course, modifications of material as well as of the form selected for illustration, will suggest themselves, and these and other modifications to which the invention is susceptible, need not be illustrated, as modifications within the spirit and scope of the invention as herein described and pointed out in the claims, will be obvious to those skilled in the art.

What I claim is:-

1. A sash pulley having a sheave, a housing to seat in a mounting frame and adapted for clamping engagement with a front and a rear surface of said frame, and having side walls between which the sheave is positioned, said walls being adapted for reciprocal movement to and from each other at one end thereof, and a face plate movably connected to said housing, and means in cooperation with the face plate and housing whereby said face plate is first brought into movable engagement with the housing at one end

thereof and then moved bodily towards the opposite end of the housing in sliding engagement with the housing to removably lock the housing and pulley to the mounting frame.

2. A sash pulley comprising a pulley, a yoke shaped housing therefor having its loop at the upper end and its free ends open at the bottom thereof, a tongue projecting upwardly from the loop to engage the rear face of a mounting frame, projections formed at the free ends of said yoke to engage the rear face of the mounting frame at the lower end of said housing, a face plate for said housing having a rearwardly projecting tongue in engagement at its free end with the free ends of said yoke, and forming a fulcrum for the movement of said face plate vertically relative to said housing, and latch mechanism serving to latch and release the upper end of said face plate relative to said housing, said latch mechanism being adapted to be tripped and released by pressure of the face plate toward the front of the mounting frame in inserting the housing into position in the mounting frame.

3. A sheave housing comprising, a casing, with means for engaging a mounting frame, irrespective of a considerable range in thickness of the particular mounting frame engaged, and adapted to seat in an aperture in said frame and to serve as a journal support for a sheave, a face plate, centrally apertured and having an upper and a lower rearwardly disposed tongue, complementary interlocking and engaging means on said tongues and on the casing to connect the face plate in limitedly movable reciprocal engagement with the casing and to maintain said face plate in selected open or closed position at one end, relative to the casing, and means, in cooperation with the end of the aperture in the mounting frame, to take the upwardly thrust of the casing when positioned in said aperture, and releasably lock the housing to the mounting frame.

4. A sheave housing comprising, a casing, to serve as a mount for a sheave and to fit into an aperture in a mounting frame and provided with means to engage the mounting frame irrespective of a considerable range in thickness of the particular mounting frame engaged, and prevent inwardly and out-

wardly movement of the casing when positioned in said aperture, and having side walls, inwardly turned at their lower ends, adapted for reciprocal movement, and a face plate, having a lower, rearwardly projecting, tongue adapted for slidably and wedgingly engagement with the reciprocative walls of the casing, to secure the face plate in reciprocal engagement with the casing, an upper, inwardly and upwardly bent, tongue, adapted, in cooperation with the upper end of the casing, to limit the range in reciprocal movement of the face plate and, in cooperation with said end and with the reciprocative walls of the casing, maintain said plate in selective position relative to the casing, and to provide means, operative to arrest upwardly movement of the casing when positioned in the aperture in the mounting frame and lock the housing to said frame.

5. A sheave housing comprising, a casing, to serve as a journal support for a sheave and to fit into an aperture in a mounting frame and having at its upper end a forwardly facing, resistibly yielding projection to engage the rear face of the mounting frame, irrespective of a considerable range in thickness of the particular mounting frame engaged, and prevent outwardly movement of the upper end of the casing when positioned in said aperture, and having side walls adapted for reciprocal movement and provided with a lower extension having a forwardly facing, downwardly and rearwardly beveled part, to engage the lower rear edge of the aperture in the mounting frame and to embed therein, with a backwardly forcing tendency, more or less as may be required by the range in thickness of the particular mounting frame engaged, to draw back and hold the lower end of the casing against outwardly movement from said aperture, and with means to engage a front face of the mounting frame and arrest movement of the casing in one direction into said aperture, and a face plate, reciprocally mounted on the casing, adapted, in cooperation therewith and with the mounting frame, to lock the housing to the mounting frame.

Executed at Cincinnati, Ohio, this 19th day of September, 1922.

JAMES H. FOOTE.
